UNITED STATES PATENT OFFICE.

JOSEPH MAYER, OF RUTHERFORD, NEW JERSEY.

ELECTRIC RAILWAY.

No. 894,964.

Specification of Letters Patent.

Patented Aug. 4, 1908.

Application filed September 13, 1907. Serial No. 392,613.

To all whom it may concern:

Be it known that I, JOSEPH MAYER, a citizen of the United States, and a resident of Rutherford, in the county of Bergen and 5 State of New Jersey, have invented a certain new and useful Improvement in Electric Railways, of which the following is a specification.

The present invention relates to sliding bows intended for use on electric railways, and more particularly to the sliding bows used on high speed electric railways, the object of the invention being to reduce the variations of pressure on the conductor due 15 to the effects of centrifugal force.

The invention consists of features of construction, arrangements and combinations of devices hereinafter described and more particularly pointed out in the appended 20 claims.

The invention is embodied in the bow illustrated in the accompanying drawing, forming part hereof, in which—

Figure 1 is a side elevation; Fig. 2 is a 25 plan of one end of the shaft 8; Fig. 3 is a side elevation of a detail of the connection to the sliding bow; Fig. 4 is an end elevation of parts shown in Fig. 1; and Fig. 5 is a side and an end elevation of the diamond frame.

30 The sliding bow should never leave the wire and should not exert an excessive pressure thereon. Owing to the vertical curvature of the wire in all known methods of suspension, the motion of the bow along the 35 same is not in a straight line, and when a curve is reached, there arises a centrifugal force proportional directly to the square of the train-speed and to the weights of the bow and parts rigidly attached thereto and 40 inversely to the radii of curvature of their motion. With high speeds, the force, with prior sliding bows, becomes so large as to produce excessive pressures on the wire where the radius of curvature of motion is 45 short and the wire is convex upward; and the bow leaves the wire where the radius of curvature is short and the wire is convex downward.

According to the present invention, the 50 connections between the car and the trolley wire are divided into two parts, the lower and heavier of which move more nearly in straight lines while the upper and lighter parts follow more closely the variations in 55 height of the suspended conductor or trolley wire.

Referring to the drawing by reference symbols, the reference character D marks an ordinary "diamond frame," suitably mounted on a car as usual.

The parts below the line A—B in Figs. 1 and 5 may be of any known or otherwise suitable form and operation.

Near the upper end of the diamond frame D, the tubes thereof terminate in castings 20, to which extensions 18 are suitably attached to form continuations of the tubes. To the upper ends of the extensions 18 are hinged the bars 17 by pins 15, and the bars 17 are hinged by the pins 14 to the tubes 12 (but one is shown in Figs. 1 and 2) while the extensions 18 are hinged to the same tubes or arms 12 by means of the sleeves 19 and pins 16, to allow the tubes 12 to slide up and down relatively to the upper end of the diamond frame as the last-named is raised and lowered. At their upper ends, the tubes 12 are provided with bearings 9 for the shaft 8, which is journaled in said bearings. The shaft 8 is provided with two hubs 7, to which 30 arms 5 are fastened by pins or otherwise, the hubs 7 being fast to the shaft 8 in a rigid manner. The upper ends of the arms 5 have castings 4 attached thereto, and the castings 4 are connected in a hinged manner by pins 2 35 with the sliding bow 1. The tubes 5 12, may carry metal rods 6, 13 to assist in carrying current. The shaft 8 is connected with the tubes 12 by means of a coiled spring 10 at each end of the shaft, each spring having one 40 end secured to the tube or shaft 8 and the other end secured to the tube 12 or bearing 9 adjacent to that end of the shaft 8. The springs 10 are wound and under compression 45 to lift the bow 1 toward the trolley wire. Inside of the springs 10 are other springs 11, which act in a direction the reverse of that in which the springs 10 act. The springs 11 have one end made fast to the shaft 8 by eyes, and the other ends of said springs 11 50 extend underneath the tubes 12 or the bearings 9, and said springs 11 are so wound and under compression that as the shaft 8 is rotated by the downward motion of the radial arms 5, they exert less and less pressure on 55 the radial arms 5, and even cease altogether to act thereon.

The sliding bow 1 is built up of three channels 3, preferably of aluminum, which are riveted together in such wise that the upper 60 surface of the middle channel is somewhat lower than the upper surfaces of the two out-

side channels, thus providing a gutter serving as a receptacle for a lubricant.

The operation of the above-described devices is as follows: The springs 10 lift the sliding bow 1 at all times, while the springs 11 are active only while the radial arms 5 point steeply upwards; when the arms 5 are in their lower positions, the springs 11 are idle. With a high train speed and a head wind and the arms 5 pointing backward, the wind-pressure tends to press the arms 5 and the bow 1 down. But if the arms 5 point forward, the wind pressure, in such case, tends to lift the arms and the bow. In the first case, the remaining range of motion downward of the arms is reduced, while in the latter case the remaining range of the upward motion of said parts is reduced. The office of the springs 11 is to minimize or reduce the above-referred-to reduction in the available range of motion of the arms 5. The use of two oppositely acting springs at each arm 5 permits, with a given change of contact-pressure, a larger range of relative motion vertically of shaft and bow than could be obtained with only one spring at each arm. As the diamond frame expands and contracts vertically, the tubes 12 slide in the sleeves 19 named.

30 When the method of suspension of the contact-wire, its size, and the maximum train speed are given, the length of the radial arms 5, the required stiffness and size of the main springs 10 and the reverse springs 11, as well as the needed static contact-pressure to secure smooth running of the bow without excessive pressure can be calculated.

What I claim as new and desire to secure by Letters Patent of the United States is—

1. In electric railways, a diamond frame 40 extended beyond its apex, links pivotally connected with said extended parts and with each other, arms pivotally connected with the upper ends of said links and slidably connected with the diamond-frame, a shaft journaled in said arms and spring-connected therewith, and arms rigidly connected with said shaft, combined with a sliding bow pivotally connected with the last-named arms.

2. In electric railways, two diamond 50 frames one above the other, tubes pivotally connected with the apex of the upper diamond-frame and slidably connected with the pivots between said frames, a shaft journaled on said tubes, main and reverse-springs for connecting said shaft with said tubes, arms rigidly connected with said shaft, and a sliding bow pivotally connected with said arms, in combination.

3. In electric railways, arms forming extensions of the diamond-frame, links pivotally connected with said arms and with each other, tubes 12 pivotally connected with said links and slidably connected with said arms, a shaft journaled on said tubes, 60 springs 65 having their ends connected fast to said shaft and to said tubes, other two springs having each one end fast to said shaft and the other end bearing against said tubes, and a sliding bow connected with said shaft, in combination.

Signed at New York city in the county of New York and State of New York this twelfth day of September, A. D. 1907.

JOSEPH MAYER.
